UNITED STATES PATENT OFFICE

FREDERICK JOSEPH WEST AND ERNEST WEST, OF MANCHESTER, ENGLAND, ASSIGNOR
TO WEST'S GAS IMPROVEMENT COMPANY LIMITED, OF MANCHESTER, ENGLAND, A
BRITISH COMPANY

COKE DISCHARGER FOR RETORTS FOR THE CARBONIZATION OF COAL AND THE LIKE

Application filed March 14, 1932, Serial No. 598,852, and in Great Britain May 7, 1931.

This invention relates to coke discharging means for vertical retorts for the carbonization of coal and the like, and has for its object to provide improved and simplified discharging means of the intermittently operating type.

The invention comprises a pivotally mounted coke chamber forming a closed receptacle for the coke with a hinged coke discharge door and locking means therefor at one side thereof, and an arcuate projection for closing the connection between the coke chamber and the retort at the opposite side thereof, and means for raising and lowering the coke chamber to make a gas tight joint between the arcuate projection and the bottom of the retort and for removing any pressure between said parts to facilitate their relative movements.

20 The invention further comprises the arrangement in which the coke chamber is carried by eccentrics upon a shaft beneath it about which the chamber pivots, the shaft being turned to raise and to lower the coke chamber.

25 The invention further comprises the arrangement in which the coke chamber has a fixed bottom sloping downwards towards the side of the chamber at which the discharge door is situated, the said door extending to the level of the bottom of the chamber and when released by its catch opening automatically to permit of coke discharge.

30 The invention further comprises the arrangement in which the coke discharge door is hinged or pivoted at its upper end and constitutes practically the whole of one side of the coke chamber.

35 The invention further comprises securing means for the coke discharge door which project through the bottom of the coke chamber and are operated by a handle upon a cross shaft beneath the coke chamber, and a spring holding the securing means normally in service.

40 The invention further comprises the provision of a table movable up and down within the coke chamber in order to control the rate of descent of coke into such chamber from the retort.

Referring to the accompanying explanatory drawings:—

Figure 1 is an elevation partly in section, illustrating the lower portion of a retort with coke discharging means thereon arranged in one convenient form in accordance with this invention.

Figure 2 is an elevation, also partly in section, taken at right angles to Figure 1.

Figure 3 is a view similar to Figure 1 (but with certain parts omitted), showing the coke chamber in position to receive coke from the retort.

Figure 4 is a sectional elevation showing a modified construction of the coke discharging means.

The same reference letters in the different views indicate the same or similar parts.

In the construction shown in Figures 1-3, we employ a pivotally mounted coke chamber *a* which is adapted when coke discharge is to be effected to be brought to the position shown in Figure 3, beneath the steaming chamber *b* which is an extension of the retort proper *c*, so that the coke can drop into the coke chamber which is then swung to the position shown in Figure 1 with an arcuate projection *d* at its upper end closing off the lower end of the steaming chamber *b* of the retort, and a door *e* at the side of the coke chamber being opened to permit the discharge of the chamber contents.

45 The coke chamber is pivoted at its lower end, the pivot shaft *f* having eccentric bushes *g* secured thereon which turn in parts *h* upon the underside of the coke chamber, so as to apply sealing pressure between the arcuate projection *d* on the coke chamber and the bottom of the steaming chamber *b* to make a gas tight joint between the said parts.

50 The pivotal shaft *f* has a pair of slotted crank arms *i* thereon in which engage the ends of a cross head *j* upon a screwed shaft *k* having a hand wheel *m* thereon. It will be seen, therefore, that by turning the hand-wheel *m* in one or other direction, the pivotal shaft can be turned to cause the eccentrics *g* either (1) to raise the coke chamber *a* and cause the part *d* to make a gas tight joint with the bottom of the steaming chamber *b*, 55 or (2) to lower the coke chamber *a* so that the coke chamber *a* is in a horizontal position, 60 so that the coke chamber *a* can be tilted to facilitate the discharge of coke from the coke chamber *a* into the steaming chamber *b*.

or (2) to lower the coke chamber to allow it to be turned freely from the Figure 1 to the Figure 3 position, and vice versa.

It will be understood that the coke chamber is only brought into line with the retort and steaming chamber, as shown in Figure 3, when coke discharge is to be effected and then only for the short period necessary for coke to fall into the chamber.

- 10 The delivery door *e* upon the coke chamber extends the full width and practically the full depth of the latter. It is hinged at *e*¹ at its upper end and when the coke chamber is in the delivery position, the release of the door catch as *n* will result in the door opening and moving to a vertical position, as shown in Figure 1. The bottom *o* of the coke chamber inclines downwards towards the door side of the chamber to facilitate coke delivery through the door.

Two catches as *n* extend through holes in the bottom *o* of the coke chamber and are carried by arms *p* upon a cross shaft *q* which is turned by a handle *r* against the pressure of a spring *t* which tends to hold the catches normally in their service positions, as shown in Figure 1.

The coke chamber *a* is turned about its pivot shaft *f* by the crank arm *u* and connecting link *v*. The crank arm is turned by the worm wheel *w* and worm *x*, the latter being upon a vertical shaft *y* with a handle *z* upon its lower end. A pawl (not shown) can engage the toothed part 3 upon the shaft *y* to prevent return movement of such shaft.

In cases where it is not desired to allow the coke to drop to the bottom of the coke chamber when the latter is brought into line with the retort, a platform 4 (see Figure 4) in the chamber *a* may be raised to the top of the chamber to support the coke and then lowered into the chamber, after which the coke is discharged through the door *e* at the chamber side. Such table 4 (which has an inclined top) may have a long stem-like part 5 projecting from the bottom of the chamber and guided in suitable guides 6. A chain or rope 7 passes from a fixed anchorage 8 over pulleys 9 and 10 to a drum 11 which can be turned by hand or otherwise to raise the table 4 or to control the rate of descent of the table. The swivelling of the coke chamber is, in the Figure 4 arrangement, effected by the pinion 12 and curved rack 13.

The swivelling of the coke chamber may be effected by hand for small installations. Before the said chamber is turned from one position to the other, the sealing pressure between the projection *d* on the chamber and the bottom of the steaming chamber *b* is released by turning the shaft *f* with the eccentrics *g* thereon.

The capacity of the coke chamber may be small relatively to that of the retort and

steaming chamber, and coke discharge be effected more frequently.

Steam is admitted to the steaming chamber in the usual way to produce water gas. It may also be admitted to the coke chamber to cool the coke prior to discharge.

What is claimed is:—

1. In coke extractors for vertical retorts, the combination of a pivotally mounted coke chamber having a hinged coke discharge door and locking means therefor at one side thereof and an arcuate projection for closing the connection between said coke chamber and the retort at the opposite side thereof, and manually operable means for raising and lowering said coke chamber to make a gas-tight joint between said arcuate projection and the retort and for removing any pressure between said arcuate projection and the retort to facilitate their relative movements. 75

2. In coke extractors for vertical retorts, the combination of a pivotally mounted coke chamber having a hinged coke discharge door and locking means therefore at one side thereof and an arcuate projection for closing the connection between said coke chamber and the retort at the opposite side thereof, a shaft beneath said coke chamber upon which said coke chamber pivots, eccentrics upon said shaft associated with said coke chamber, and means for turning said shaft to raise and lower said coke chamber to make a gas-tight joint between said arcuate projection and the retort and to remove any pressure between said arcuate projection and the retort to facilitate their relative movements. 90

3. In coke extractors for vertical retorts, the combination of a pivotally mounted coke chamber having a hinged coke discharge door and locking means therefor at one side thereof, an arcuate projection for closing the connection between said coke chamber and the retort at the opposite side thereof and a fixed bottom sloping downwards towards said side at which said coke discharge door is situated, and manually operable means for raising and lowering said coke chamber to make a gas-tight joint between said arcuate projection and the retort and for removing any pressure between said arcuate projection and the retort to facilitate their relative movements, said coke discharge door extending to the lower level of said fixed bottom and opening automatically when said locking means are released. 105

4. In coke extractors for vertical retorts, the combination of a pivotally mounted coke chamber having a hinged coke discharge door and locking means therefor at one side thereof, an arcuate projection for closing the connection between said coke chamber and the retort at the opposite side thereof and a fixed bottom sloping downwards towards said side at which said discharge door is situated, a shaft beneath said coke chamber upon which 120

said coke chamber pivots, eccentrics upon said shaft associated with said coke chamber, and means for turning said shaft to raise and lower said coke chamber to make a gas-tight 5 joint between said arcuate projection and the retort and to remove any pressure between said arcuate projection and the retort to facilitate their relative movements, said coke discharge door extending to the lower level 10 of said fixed bottom and opening automatically when said locking means are released.

5. In coke extractors for vertical retorts, the combination of a pivotally mounted coke chamber having a coke discharge door hinged 15 at its upper end and constituting practically the whole of one side thereof and locking means therefor and an arcuate projection for closing the connection between said coke chamber and the retort at the opposite side 20 thereof, and manually operable means for raising and lowering said coke chamber to make a gas-tight joint between said arcuate projection and the retort for removing any pressure between said arcuate projection and 25 the retort to facilitate their relative movements.

6. In coke extractors for vertical retorts, the combination of a pivotally mounted coke chamber having a coke discharge door hinged 30 at its upper end and constituting practically the whole of one side thereof and locking means therefor and an arcuate projection for closing the connection between said coke chamber and the retort at the opposite side 35 thereof, a shaft beneath said coke chamber upon which said coke chamber pivots, eccentrics upon said shaft associated with said coke chamber, and means for turning said shaft to raise and lower said coke chamber to make a gas-tight joint between said arcuate projection and the retort and to remove any pressure between said arcuate projection and the retort to facilitate their relative movements.

40 7. In coke extractors for vertical retorts, the combination of a pivotally mounted coke chamber having a coke discharge door hinged at its upper end and constituting practically the whole of one side thereof and locking means therefor, an arcuate projection for closing the connection between said coke chamber and the retort at the opposite side thereof, and a fixed bottom sloping downwards towards said side at which said coke 45 discharge door is situated, and manually operable means for raising and lowering said coke chamber to make a gas-tight joint between said arcuate projection and the retort and for removing any pressure between said arcuate projection and the retort to facilitate their relative movements, said coke discharge door extending to the lower level of said fixed bottom and opening automatically when said locking means are released.

45 8. In coke extractors for vertical retorts,

the combination of a pivotally mounted coke chamber having a coke discharge door hinged at its upper end, constituting practically the whole of one side thereof and locking means therefor which project through the bottom 70 of said coke chamber, and an arcuate projection for closing the connection between said coke chamber and the retort at the opposite side thereof, a cross shaft beneath said coke chamber, a handle upon said cross shaft for operating said locking means, a spring holding the locking means normally in service, and manually operable means for raising and lowering said coke chamber to make a gas-tight joint between said arcuate projection 75 and the retort and for removing any pressure between said arcuate projection and the retort to facilitate their relative movements.

9. In coke extractors for vertical retorts, the combination of a pivotally mounted coke chamber having a hinged coke discharge door and locking means therefor at one side thereof and an arcuate projection for closing the connection between said coke chamber and the retort at the opposite side thereof, a table 80 movable up and down within said coke chamber, and manually operable means for raising and lowering said coke chamber to make a gas-tight joint between said arcuate projection and the retort and for removing any pressure between said arcuate projection and the retort to facilitate their relative movements.

10. In coke extractors for vertical retorts, the combination of a pivotally mounted coke chamber having a hinged coke discharge door and locking means therefor at one side thereof, a bottom, and an arcuate projection for closing the connection between said coke chamber and the retort at the opposite side thereof, a table movable up and down within said coke chamber, a stem-like part for said table projecting through and guided in said coke chamber bottom, a pulley upon said stem-like part, a pulley upon the said coke chamber, a flexible element passing over said pulleys, and manually operable means for raising and lowering said coke chamber to make a gas-tight joint between said arcuate projection and the retort and for removing any pressure between said arcuate projection and the retort to facilitate their relative movements.

In testimony whereof we have signed our names to this specification.

FREDERICK JOSEPH WEST.
ERNEST WEST.
